UNITED STATES PATENT OFFICE.

FRITZ EGERSDÖRFER, OF CHARLOTTENBURG, GERMANY.

FEED PUMP FOR COMBUSTION ENGINES.

Application filed September 10, 1920. Serial No. 409,503.

(GRANTED UNDER THE PROVISIONS OF THE ACT OF MARCH 3, 1921, 41 STAT. L., 1313.)

To all whom it may concern:

Be it known that I, FRITZ EGERSDÖRFER, a citizen of Germany, residing at Charlottenburg, Germany, have invented certain new and useful Improvements in Feed Pumps for Combustion Engines (for which I filed application in Germany, filed July 20, 1914, No. 303,205, and application in Germany, filed March 15, 1917, No. 360,863; application in France, filed May 30, 1919, No. 518,583; application in Great Britain, filed July 9, 1920, No. 148,157; application in Italy, filed Sept. 10, 1919, No. 275,151; application in Sweden, filed April 24, 1919, No. 48,684; application in Norway, filed May 16, 1919, No. 36333; application in Denmark, filed May 5th, 1919, No. 30137; application in Spain, filed May 23, 1919, No. 69865; application in Switzerland, filed May 10, 1919, No. 94534; application in Czechoslovakia, filed September 5, 1919 (not yet allowed); application in Holland, filed June 6, 1919, No. 8005); and I do hereby declare the following to be a full, clear, and exact description of the invention, such as will enable others skilled in the art to which it appertains to make and use the same.

My invention relates to improvements in feed pumps for internal-combustion engines. It has heretofore been proposed to feed the motor charge to internal-combustion engines by means of small pumps provided with reciprocating pistons. I have found that the operation of such feed pumps is unsatisfactory, because, by reason of the suction and pressure valves provided in the pump, it is impossible to feed accurate amounts of fuel to the engine,—amounts which frequently are not more than a fraction of a cubic centimeter. Furthermore feed pumps of this construction are objectionable by reason of the high number of revolutions of the engine and the high number of the strokes required of the pump, which under normal conditions amounts to 500 per minute and more. The object of the improvements is to provide apparatus for feeding fuel, air, or combustible mixture to the motor cylinder, adapted to feed accurately measured amounts to the cylinder, and

which need not be more than a fraction of a cubic centimeter, and apparatus which can be operated at high speed. With this object in view my invention consists in connecting the fuel supply pipe to the motor through a rotary pump. A rotary pump is a valveless pump, it can be operated at high speed, because its movable parts are always moving in the same direction and it is not subject to inertia, and it is adapted to supply minimum and measured amounts of fuel or air or combustible mixture at maximum speed. The amount of air or fuel or combustible mixture supplied by the rotary pump can be varied from zero to a maximum, so that the pump answers all requirements of the operation of the engine. The movable parts of the pump are perfectly enclosed within a casing and they require no lubrication, because they are lubricated by the fuel itself.

The rotary pump may communicate directly with the cylinder of the combustion engine without the necessity of providing check valves between, and the fuel may be projected directly into the cylinder, so that the objectionable long suction pipes and other objectionable chambers are dispensed with.

My invention also relates to an improved construction of the pump which particularly adapts the same to be used as a feed pump for internal-combustion engines. Particularly in case of small engines operated at high speeds, each charge of the cylinder requires a very small amount of fuel to be supplied. In such cases rotary pumps of the construction now in use are not well adapted to be used as feed pumps, because they cannot feed such small amounts. Furthermore it is not possible by means of such pumps to vary the amount of fuel for each stroke and thereby to regulate the supply of fuel to the motor. For example, if an internal-combustion engine consumes for each H. P. per hour 230 grammes of benzine, a four cylinder motor of 15 H. P. and 1000 revolutions per minute consumes 2450 grammes of benzine per hour. Therefore each cylinder consumes 863 grammes per hour or about 15 grammes per minute. As the cylinder performs 500 suction strokes per minute each stroke consumes 0.03 of a

pumps of known construction such a small and accurately measured amount cannot be fed to the cylinder, even if the said pumps are provided with a single valve,—this because of leakage and inaccurate operation of the rotating parts. Regulation of such a small amount is impossible, because regulating mechanisms do not operate with sufficient accuracy, and as far as I am aware such regulating apparatus has not heretofore been provided.

I have found that all requirements of successful operation of an internal-combustion engine are fully answered by a rotary pump of that class in which one or more pistons or plungers are mounted for reciprocation within a rotary drum and eccentrically of the axis of rotation, and in which a cam disk is provided for reciprocating the said pistons or plungers, the cam disk being adapted to be changed in its relative position for regulating the stroke of the pistons. The pistons or plungers of such a pump have circular cross-sections and they can be mounted within their cylindrical chambers in an absolutely tight manner, and by varying the position of the cam the length of the stroke of the pistons or plungers can be fixed at any desired amount from zero to a maximum. The said cam may be set independently of the numbers of revolutions of the pump, and while pump and engine are in operation. When the said cam is disposed with its operative face perpendicular to the axis of rotation, the stroke of the pistons or plungers within their cylindrical chambers is zero, so that no fuel is fed to the cylinder. Proportionately as the inclination of the cam is increased, the piston stroke is increased and the amount of fluid supplied by the pump is increased.

It will therefore be understood, that the amount of fluid supplied by the pump may be regulated from zero to a maximum independently of the number of revolutions. As the cam does not take part in the rotation of the pump and is stationary relatively to the pump, it may be so connected with the governor of the engine, that the fuel supplied to the cylinder will be automatically controlled by the said governor.

The said construction of the rotary pump is particularly adapted for use in connection with multi-cylinder engines, because in such engines for each cylinder a pump piston or plunger may be provided within the same rotary member, and the cylindrical chambers of plungers will then be connected one with each of the motor cylinders. Therefore a single pump is provided for all the cylinders, but each cylinder receives its fuel, or air, or combustible mixture independently of the other cylinders. Thereby premature combustion of the fuel or combustible mixture and whirls within the supply pipes to

the cylinders and accordingly non-uniform supply and non-uniform operation of the motor are avoided.

The pump is such as is described in my co-pending application for United States Letters Patent filed September 10th, 1920, Serial No. 409,594.

For the purpose of explaining the invention several examples embodying the same are shown in the accompanying drawings. In said drawings—

Fig. 1 is a longitudinal section of a feed pump,

Fig. 2 is a cross-section taken on the line A—A of Fig. 1,

Fig. 2^a is a modification of the mechanism shown in Fig. 2,

Fig. 3 is a side view of the rear parts of the pump showing the mechanism for setting the cam,

Fig. 3^a is a modification of the mechanism shown in Fig. 3,

Fig. 4 is a view of a motor provided with a feed pump,

Fig. 5 is a side view of a pump provided with automatic setting mechanism for the cam and in connection with a carburetor,

Figs. 6 to 9 are cross-sections of the pump showing several examples of the construction of the inlet and outlet ports, and

Fig. 10 is a longitudinal section showing a modification of the piston of the pump.

The same numerals of reference have been used in all the views to indicate corresponding parts.

Referring to the example shown in Fig. 1, to a rotary shaft 10 a rotary body or drum 11 is secured which is rotatably mounted within a cylindrical casing 12 and is formed with two cylindrical chambers or pockets 13 disposed lengthwise and eccentrically of the axis of rotation of the drum. Within each of the said pockets a plunger or piston is mounted for reciprocation, and one of the said plungers which has been indicated by the numeral 14 is the feeding plunger, while the other one which has been indicated by the numeral 15 is provided for retracting the plunger 14 from its pocket after performing the pressure stroke. Accordingly only the pocket 13 within which the plunger 14 is located is adapted to be alternately connected with inlet and outlet ports, while the pocket 13 containing the plunger 15 is closed as against said ports.

The ends of the plungers 14 and 15 which project from the cylindrical chambers 13 carry slide shoes 16 which have universal movement on the plungers and which have flat sliding or bearing faces. As shown the plungers and shoes 16 have spherical bearing surfaces. The flat sliding or bearing faces of the shoes 16 are engaged by a cam 17 which as shown is in the form of an inclined disk. The said disk 17 is made in-

tegral with two pivots 18 and 19 (Figs. 2 and 3) by means of which the said disk is supported within suitable bearings provided in the wall of the casing 12. By thus being supported on the pivots 18 and 19 the disk 17 may be rocked in such a way, that the plain cam face of the disk which engages the slide shoes 16 may be set either in a position perpendicular to the axis of rotation of the drum 11, or in any position inclined to the said axis. An inclined position is shown in Fig. 1. The plungers 14 and 15 are connected by a rocker 20 which is supported on the rotary parts 10, 11. In the construction shown in Fig. 1 the said rocker is mounted within a slot formed in the shaft 10. The rocker is so connected with the plungers 14 and 15, as to transmit movement from one to the other, so that the 20 plungers move in opposite directions. When the drum 11 is rotated by suitable mechanism, for example by means of a gear wheel 21, the plungers 14 and 15 slide with their shoes 16 on the inclined cam disk 17, and in such movement the plungers 14 and 15 are always held in contact with the cam disk by means of the rocker 20, so that the rotary movement of the drum 11 is transformed into reciprocating movement of the plungers.

The feed pump shown in Fig. 1 is designed for use in connection with a two-cylinder motor performing successive suction strokes. A motor of this construction requires a single feed plunger 14 when the number of revolutions of the pump is one half of that of the engine. The rear end of the cylindrical pocket 13 of the plunger 14 is adapted to be connected by a port 22 with a pressure passage 23 and a suction passage 24 alternately. In the preferred form shown in Fig. 1 the said pressure and suction passages are formed in a removable annular disk 25, which is shown in detail in Fig. 6.

For setting the cam disk 17 in its different inclined positions the outer end of the pivot 18 carries a toothed sector 26 which is adapted to be operated by a worm 27. The worm 27 can be operated in different ways. In the example shown in Fig. 3 it carries a milled disk 28 for operation of the worm by hand. In the modification shown in Fig. 2^a, instead of the worm 27 a crank 29 is secured to the shaft 18, and in the modification shown in Fig. 3^a the worm 27 is connected with a crank 29^a.

Upon each rotation of the drum 11 the reciprocating plunger 14 performs a suction and a pressure stroke. If the pump is designed for feeding liquid fuel, the said fuel is supplied to the pump through a passage 30 and it is discharged therefrom through a passage 31. The latter is connected with a nozzle 32, as is shown in Fig. 4, which by

sage of the fuel causes the pressure required for injecting the fuel. The pump is constructed in such a way, that for each rotation of the drum 11 the feed plunger 14 supplies the fuel to the cylinders when the said cylinders perform their suction strokes.

As appears from Fig. 4, the nozzle 32 is disposed within the mixing chamber of a carburetor 33, and within the said mixing chamber a disk 34 is disposed in front of the discharge end of the nozzle, by means of which the fuel supplied to the mixing chamber is sprayed into the surrounding air. For driving the pump the gear wheel 21 keyed to the shaft 10 is in engagement with a gear wheel 35 which is in mesh with a gear wheel 36 keyed to the gear shaft of the engine.

For regulating the amount of fuel supplied by the pump the cam disk 17 is rocked more or less by means of the milled head 28 or the crank 29 or 29^a. In the example shown in Figs. 4 and 5 the crank 29 is connected by a rod 37 with a crank 38 connected with the governor. Therefore the cam disk is set and the supply of fuel regulated automatically by the governor.

For varying the supply of air according to the supply of fuel the inlet to the carburetor 33 is provided with a throttle member 39, which as shown is connected by a lever 40 and a link 41 with the rod 37, so that the said throttle member is set together with the cam.

In the example shown in Fig. 5 the whole stroke of the feed plunger 14 is used for supplying the fuel to the cylinders. In Fig. 7 I have shown by way of modification a pump designed for feeding fuel to a one-cylinder internal-combustion engine. In this case the pressure passage 23 and the suction passage 24 formed through disk 25 extend, not as in Fig. 6 through approximately 180° of the circumferential path of port 22, but through approximately 90°. Comparatively large spaces are left between the passages so that only one half of the suction and pressure strokes of the plunger is made use of.

In Fig. 8 I have shown an example of a pump, a plurality of which are provided for a multi-cylinder engine, each pump supplying fuel for one of the cylinders. As in this case only during small portions of the revolution of the plunger fuel is drawn into and forced out of the cylindrical pocket, the vacuum and the pressure produced during the suction and pressure strokes would be excessive if no provision of relief were adopted. To avoid this the suction passage 24 extends over approximately three quarters of the circumferential path of the cylindrical pocket 13, while the pressure passage 23 extends over approximately one quarter of the said path. Therefore pressure which other-

wise would accumulate within the pocket 13 prior to discharging the fuel from the pump is avoided by a forcing back of the fuel into the suction passage during part of the pressure stroke.

In Fig. 9 I have shown a modification in which the pressure passage 23' is disposed not within the annular disk 25 but within the drum 11, as is shown in broken lines. In 10 this case the passage 23' takes part in the rotation of the drum 11. The stationary disk may be provided with a corresponding port.

While in the examples shown in the figures 15 the suction and pressure passages are provided at the head side of the drum 11 I wish it to be understood that my invention is not limited to arranging the said passages at this part of the drum.

20 In Fig. 10 I have shown a modification in which the plunger 14 is forced out of its pocket and into contact with disk 17 by means of a spring 42 which is compressed when the plunger is forced into the pocket 25 by the cam disk for performing its pressure stroke, and which during the suction stroke forces the plunger in contact with the cam disk and at the same time provides the power for drawing in the fuel. This construction will be preferable in such cases in 30 which more than two feed plungers are provided within the rotary drum 11. Such pumps which are provided with several pistons are particularly adapted for use in connection with multi-cylinder motors, in 35 which each cylinder is equipped with feeding means of its own, because in such cases instead of separate pumps a single feed pump can be provided for all the cylinders, 40 the pump being provided with a corresponding number of feed plungers for supplying the fuel to the individual cylinders.

I claim herein as my invention:

1. In a combustion engine, the combination, 45 with the cylinder, and the supply for the charge thereto, of a feed pump connected with said supply and with said cylinder and comprising a stationary casing provided with suction and pressure ducts, and a rotary member provided with a pressure chamber which is adapted upon rotation alternately to be opened to one and another of said ducts and to be closed by the 50 wall of the casing and to have its capacity alternately reduced and increased.

2. In a combustion engine, the combination, 55 with the cylinder, and the supply for the charge thereto, of a feed pump connected with said supply and with said cylinder and comprising a casing provided with suction and pressure ducts, a member within 60 said casing provided with a pressure chamber, and means to impart relative rotary movement to said casing and member, said 65 pressure chamber being adapted upon ro-

tation alternately to be opened to one and another of said ducts and to be closed by the wall of the casing and to have its capacity alternately reduced and increased.

3. In a combustion engine, the combination, 70 with the cylinder, and the supply for the charge thereto, of a feed pump connected with said supply and with said cylinder and comprising a rotary cylindrical member having a cylindrical chamber disposed lengthwise of and eccentric to the axis of rotation, a stationary member having suction and pressure ducts adapted as the cylindrical member rotates alternately to communicate with said cylindrical chamber, a piston mounted for reciprocation in said cylindrical chamber, a cam engaging said piston and adapted upon rotation of said cylinder member to move the piston in one direction, and means to move the piston in 75 the opposite direction.

4. In a combustion engine, the combination, 80 with the cylinder, and the supply for the charge thereto, of a feed pump connected with said supply and with said cylinder and comprising a rotary cylindrical member having a cylindrical chamber disposed lengthwise of and eccentric to the axis of rotation, a stationary member having suction and pressure ducts adapted as 85 the cylindrical member rotates alternately to communicate with said cylindrical chamber, a piston mounted for reciprocation in said cylindrical chamber, an angularly disposed cam engaging said piston and adapted 90 upon rotation of said cylinder member to move the piston in one direction, means to move the piston in the opposite direction, and means to vary the degree of angularity 95 of said cam.

5. In a combustion engine, the combination, 100 with the cylinder, and the supply for the charge thereto, of a feed pump connected with said supply and with said cylinder and comprising a cylindrical member having a cylindrical chamber, a casing, a cam, means to rotate said cam and casing on the one hand and cylinder member on the other hand relatively to each other, said cylindrical chamber being disposed eccentrically 105 to and lengthwise of the axis of the relative rotation, a piston within said cylindrical chamber engaged by said cam for movement in one direction, and means to move said piston in the opposite direction, said 110 casing being provided with suction and pressure ducts adapted as the parts rotate to communicate alternately with the cylindrical chamber in the said cylindrical member.

6. In a combustion engine, the combination, 115 with the cylinder, and the supply for the charge thereto, of a feed pump connected with said supply and with said cylinder and comprising a cylindrical member having a cylindrical chamber, a casing, a 120

cam, with face angularly disposed to the axis of the cylindrical chamber in the cylindrical member, means to rotate said cam and casing on the one hand and cylindrical member on the other hand relatively to each other, said cylindrical chamber being disposed eccentrically to and lengthwise of the axis of the relative rotation, a piston within said cylindrical chamber engaged by said

5 cam for movement in one direction, means

to move said piston in the opposite direction, and means to set said cam relatively to the piston in different positions, said casing being provided with suction and pressure ducts adapted as the parts rotate to communicate alternately to the cylindrical chamber in the cylindrical member.

15 In testimony whereof I hereunto affix my signature.

FRITZ EGERSDÖRFER.
